PAIR OF SUNGLASSES

Kikuo Hayashi, 2119½ Hoagland Ave.,
Fort Wayne, Ind. 46804

Filed May 11, 1967, Ser. No. 7,066

Term of patent 14 years

(Cl. D57—1)

FIG.1

FIG.2

FIG.3

FIG. 4

FIG. 8

FIG. 1 is a front elevational view of a pair of sunglasses showing my new design;

FIG. 2 is a rear perspective view thereof;

FIG. 3 is a top plan view thereof;

FIG. 4 is a cross-sectional view of the pair of sunglasses shown in FIG. 1 taken substantially along section line 4—4;

FIG. 5 is a front elevational view of a modified form of the design shown in FIGS. 1 through 4;

FIG. 6 is a rear perspective view thereof;

FIG. 7 is a top plan view thereof;

FIG. 8 is a cross-sectional view of the pair of sunglasses shown in FIG. 5 taken substantially along section line 8—8;

I claim:

The ornamental design for a pair of sunglasses, as shown and described.
